UNITED STATES PATENT OFFICE.

NICHOLAS J. KLOHN, OF ST. PAUL, MINNESOTA.

SIGNALING DEVICE FOR VEHICLES.

1,377,691.

Specification of Letters Patent. Patented May 10, 1921.

Application filed August 1, 1919. Serial No. 314,593.

To all whom it may concern:

Be it known that I, NICHOLAS J. KLOHN, a citizen of the United States, residing in St. Paul, in the county of Ramsey and State of Minnesota, have invented new and useful Improvements in Signaling Devices for Vehicles, of which the following is a specification.

My invention relates to improvements in 10 signaling devices for vehicles. It is my object to produce a signal which shall be convenient and efficient.

A further object is to provide a catch for 15 the signal adapted to hold the same temporarily out of signaling position.

A further object is to provide a strong locking mechanism to protect the device from being injured by meddlers when not in use.

20 Heretofore signaling devices provided for automobiles have usually been lacking in convenience or efficiency or susceptible to injury in use or by meddlers when not in use.

25 In the drawings which form part of this specification Figure I is a side view of my signal, with part of the housing, which encloses the operating parts, removed, and a portion of the device broken away, the signal arm with its connecting parts being 30 illustrated in full lines out of signaling position and, in dotted lines, the position it would assume when released into signaling position.

35 Fig. II is a side view of the signal with part of the housing removed and a portion of the device broken away, the signal arm being shown in the position it would assume just as it is being released into signaling position.

40 Fig. III is a side elevation of the signal with part of the housing removed and a portion of the device broken away. It illustrates the catch engaging the signal to hold 45 it temporarily until the plunger of the operating solenoid is brought into normal position to rigidly lock the signal out of signaling position.

Fig. IV is an end view of the signal, a portion of which is broken away.

Fig. V is a perspective view of a portion of the operating mechanism and the plunger which acts as the core of the solenoid.

The drawings illustrate a signaling device 55 A, composed of a signal arm B, the outer,

free end of which carries a signal head C, provided with lenses or windows 2 of any suitable color to show the light from an incandescent bulb 3 contained in the signal head C. The inner end of the signal arm B 60 is pivotally held in the housing 4 by the rock-shaft 5.

The housing 4 consists of similar pieces united by screws, and formed to inclose a solenoid and the hereinafter described actuating mechanism connecting the same with the arm B. One end of the housing 4 is cylindrical in shape and adapted to contain a solenoid 6, the plunger or movable core 7 of which is connected to the operating arms 8. 70 The arms 8 are spaced apart in parallel relation and rigidly connected by suitable rivets 9 and 10. The inner ends 11 of the arms 8 project into the slot 12 formed in the plunger 7 and are pivotally connected by 75 the pin 13 to the plunger. The outer ends of the arms 8 have slots 16 therein through which the pin 15 passes so as to be slidably held in the outer ends of the arms 8. The pawl 14 is held between the arms 8 by the 80 pin 15 which pivotally fastens the pawl to the housing 4, but said arms, when actuated by the solenoid, slide freely on either side of said pawl. Near its pivoted end, the pawl 14 is formed with a projecting tongue 85 17 which is adapted to be engaged by the rivet 9 to release the pawl from operating position.

The coil spring 18 has its bearings between upwardly projecting lugs 19 formed 90 on the arms 8, and an internal flange 4' formed in the housing 4, and tends to hold the plunger 7 partially withdrawn from the coil of the electromagnet 6. A guide rod 20 extends through the spring 18 and is fixed at 95 its ends in perforations formed between the members of the housing 4 in the above mentioned flange 4' and a second flange 4''.

The inner end of the signal arm B is bifurcated and its legs 21 straddle the disk-like 100 portion of the housing 4, and the inner surface of said legs are formed with transverse slots 22 to engage projecting feathers 23 formed on the end faces of the shaft 5, so as to rigidly key the signal arm B to the shaft 105 5, and suitable cap screws 24 are threaded in the usual way in the axial bore 25 of the shaft 5. In this manner the signal arm B is held against side motion in the housing 4 while it is freely pivoted so that it may tilt. 110

A lug 26 is formed integral with and projects from the central portion of the shaft 5. This lug is adapted to be engaged by the notch or recess 27 formed in the arms 8 when the solenoid 6 is operated to pull the signal from the dotted position, illustrated in Fig. I, out of signaling position. The lug 26 is also engaged by the pawl 14, momentarily as illustrated in Fig. III, to hold the signal 5 arm B out of signaling position and to form a temporary catch or lock to hold the signal arm against falling again into signaling position until the plunger 7 is withdrawn from the solenoid by the action of spring 18, so 10 that it will engage against the end of the lug 26 and rigidly lock the signal arm B in the vertical position. The engaging lug 26 is of stout construction so as to form a strong engagement between the signal arm 15 20 B and the plunger 7, thereby preventing anyone who may take hold of the signal arm when it is out of signaling position from jerking it into signaling position. This is an essential feature of the invention as in 25 use it has been found that there is a temptation to take hold of the signaling arm when in elevated position on the motor vehicle, and unless the construction is strong the signal may be easily broken or put out of order 30 by jerking on the signal arm B. The construction illustrated provides a simple, inexpensive and practical means for locking the signal arm out of signaling position by bringing the pawl 14 into direct engagement 35 with the plunger 7.

The housing 4 is attached in any suitable manner to the motor vehicle on which it is to be used and the solenoid 6 is connected in the usual way to a source of electrical energy, not illustrated in the drawings. A button 28, positioned on the top of the housing 4, is provided to hold the signal arm B beyond its vertical position and cause it to drop by gravity into signaling position. 40 The button 28 is pressed outward by the spring 29, and the signal arm B, when out of signaling position, is held in contact with the button 28 and compresses the spring 29 so that the arm B is under spring tension 45 50 when the signal is erect. Thus the instant the plunger 7 is released from the influence of the solenoid 6 the lug 26 is freed from the plunger 7 and the shaft 5, carrying the lug 26, together with the arm B and signal C, 55 are free to drop into signaling position.

The operation during a complete cycle is as follows: The signal arm B being erect as in Fig. 1, a short electrical impulse is given to the coil 6, which attracting the core 7, draws 60 it rapidly inward, disengaging the lug 26 from abutment against said core. At the instant disengagement occurs, the spring 29 starts the arm B on its downward movement, which rotates the lug 26 to abut against the 65 rounded end of the pawl 14 and prevents it

from falling into engagement as in the return stroke, Fig. 3. The fact that the pawl 14 does not fall into engagement is due to the relatively rapid motion of the core inward as compared with the motion of the pawl, which is actuated by gravity only. Further, the contacting ends of the pawl 14 and the lug 26 are so rounded that a slight rotation of the arm toward its signaling position prevents the pawl 14 from falling into engagement as shown in Fig. 3. The immediate cessation of the current in the coil 6, now releases the plunger, and the arm B is free to fall into signaling position.

When it is desired to raise the signal out 80 of signaling position, the solenoid is energized and pulls the plunger inward, thus causing the arms 8 to engage the lug 26 in the notch 27 to pull the signal upward out of signaling position with a quick, decisive 85 movement, throwing the signal arm B against the resilient button 28 with sufficient force to disengage the lug 26 from the notch 27 and allowing the pawl 14 to drop into engagement with the lug 26. At this instant 90 the pawl 14 forms a temporary catch for holding the signal out of signaling position, as illustrated in Fig. III. The moment the magnetic attraction of the solenoid 6 for the plunger 7 ceases (in the act of drawing the 95 signal out of signaling position) the spring 18 will automatically withdraw the plunger from the solenoid, causing the pin 9 to engage the tongue 17, thereby releasing the pawl 14 from the lug 26 while the armature 100 simultaneously comes into contact with the lug 26 to lock the signal out of signaling position and rigidly hold the arm B against movement until it is again desired to use the signal.

In operation my signal requires only a small amount of current and does not use any current while the signal arm is stationary in either vertical or horizontal position, except for the signal light 3, which is used 110 at night. Thus, it is economical in operation and practical for use, being composed of simple and comparatively inexpensive parts.

The device is so constructed that when it is desired to use the signal light 3 the arm B 115 when moving into signaling position, makes contact in the ordinary manner with the terminal pin 30, which is connected by the wire 31 to a suitable source of electrical energy, the same not being illustrated in the drawing. When the arm B and signal C are drawn out of signaling position the contact to the light 3 is broken. In this manner the signal light 3 is turned on and off automatically in the operation of the signal.

While my signal is primarily intended to be applied to an automobile, it is obvious that it may be used on other vehicles or structures without departing from the spirit of my invention.

Having described my invention, what I claim as new and desire to protect by Letters Patent is:

1. In a signal a housing adapted to be attached to an automobile, a rock-shaft journaled in one end of said housing, a signal arm on said shaft, a solenoid coil in the opposite end of said housing, a reciprocating plunger within and adapted to be energized by said coil, a lug integral with said rock-shaft and adapted to engage the outer end of said plunger when the same is projected from the coil, a pair of parallel arms pivotally attached to said outer end of the plunger, a hook formed on said arms, adapted to engage said lug to raise the signal arm and a pawl slidably and tiltably mounted in said arms and adapted to momentarily engage said lug during the upward movement of the signal arm. 20
  2. In a signal a housing adapted to be attached to an automobile, a rock-shaft journaled in one end of said housing, a signal arm on said shaft, a solenoid coil in the opposite end of said housing, a reciprocating plunger within and adapted to be energized by said coil, a lug integral with said rock-shaft and adapted to engage the outer end of said plunger when the same is projected from the coil, a pair of parallel arms attached to said outer end of the plunger with a limited pivotal movement with reference to the plunger, a hook dependent from said arms, adapted to engage said lug to raise the signal arm, an internal flange on the housing, a lug on the top of said arms, a coiled spring compressible between said flange and lug and a pawl slidably and tiltably mounted in said arms and adapted to momentarily engage said lug during the upward movement of the signal arm. 35
  3. In a signal a housing adapted to be attached to an automobile, a rock-shaft journaled in one end of said housing, a signal arm rigidly attached to said shaft, a solenoid coil in the opposite end of said housing, a reciprocating plunger slidable within said coil formed with a slot in its outer end, a lug on said rock-shaft, adapted to impinge against said plunger when the same is projected from the coil, a pair of parallel arms pivoted in said slot in the plunger, a hook formed on said arms, adapted to engage said lug and a pawl slidably and tiltably mounted between said arms and adapted to momentarily engage said lug during the upward movement of the signal arm. 50
  4. In a signal a housing adapted to be attached to an automobile, a rock-shaft journaled in one end of said housing, a signal arm on said shaft, a solenoid coil in the opposite end of said housing, a reciprocating plunger within and adapted to be energized by said coil, a lug on said rock-shaft adapted to be held by the plunger when the same
- is projected from the coil and the signal arm is erect, a pair of parallel arms pivoted in the outer end of the plunger and a hook formed on said arms, adapted to engage said lug to draw the signal arm into an upright position. 70
5. In a signal a housing adapted to be attached to an automobile, a semaphore tiltably journaled on one end of said housing, a solenoid coil in the opposite end of said housing, a reciprocating plunger within and adapted to be energized by said coil, means on the signal arm adapted to engage the outer end of said plunger when the same is projected from the coil and the semaphore is erect, an extension articulated in the outer end of the plunger, a hook formed on said extension and adapted to engage and raise the signal arm and resilient means adapted to push the semaphore over dead center to permit it to fall by gravity when the plunger is withdrawn. 80
  6. In a signal a housing adapted to be attached to an automobile, a rock-shaft journaled in one end of said housing, a semaphore arm on said shaft, a solenoid coil in the opposite end of said housing, a reciprocating plunger within and adapted to be energized by said coil, a lug formed on said rock-shaft and adapted to engage the outer end of said plunger when the same is projected from the coil, an extension attached to said plunger, a hook formed on said extension to engage said lug, a pawl slidably and tiltably mounted in said extension and adapted to momentarily engage said lug during the upward movement of the arm and means for holding said pawl out of engagement with said lug during the downward movement of the arm. 95
  7. In a signal a housing adapted to be attached to an automobile, a rock-shaft journaled in one end of said housing, a signal arm rigidly attached to said shaft, a solenoid coil in the opposite end of said housing, a reciprocating plunger slidable within said coil and formed with a slot in its outer end, a lug on said rock-shaft, adapted to impinge against said plunger when the same is projected from the coil, a pair of parallel arms pivoted in said slot in the plunger, a hook formed on said arms, adapted to engage said lug, a pawl slidably and tiltably mounted between said arms and adapted to momentarily engage said lug during the upward movement of the signal arm and means for holding said pawl out of engagement with said lug during the downward movement of the signal arm. 110
  8. In a signal a housing adapted to be attached to an automobile, a rock-shaft journaled in one end of said housing, a signal arm on said shaft, a solenoid coil in the opposite end of said housing, a reciprocating plunger within and adapted to be energized by said coil, a lug on said rock-shaft adapted to be held by the plunger when the same

by said coil, a lug integral with said rock-shaft and adapted to engage the outer end of said plunger when the same is projected from the coil, a pair of parallel arms attached to said outer end of the plunger with a limited pivotal movement with reference to the plunger, a hook dependent from said arms, adapted to engage said lug to raise the signal arm, an internal flange on the hous-

ing, a lug on the top of said arms and a 10 coiled spring compressible between said flange and lug.

In witness whereof, I have hereunto subscribed my name to this specification.

NICHOLAS J. KLOHN.
